UNITED STATES PATENT OFFICE.

LOUIS ALBERT STRAUBEL, OF GREEN BAY, WISCONSIN.

MACHINE FOR CUTTING AND INTERFOLDING SHEETS OF PAPER.

1,326,986.

Specification of Letters Patent. Patented Jan. 6, 1920.

Application filed May 23, 1918. Serial No. 236,117.

To all whom it may concern:

Be it known that I, LOUIS A. STRAUBEL, a citizen of the United States of America, residing at Green Bay, in the county of 5 Brown and State of Wisconsin, have invented certain new and useful Improvements in Machines for Cutting and Interfolding Sheets of Paper and the like, of which the following is a specification, reference being 10 had therein to the accompanying drawing.

The invention relates to new and useful improvements in machines for cutting a plurality of webs of papers transversely to form a continuous web of overlapped sheets and 15 for interfolding such sheets.

The invention more particularly relates to improvements in machines of the type described in my prior Patents #1,242,262, #1,249,550 and #1,253,644.

20 In the present invention the sheet material is cut exclusively in a transverse direction, short of the edges of the web whereby a tie of a width of approximately one inch is left uncut on each side to hold the interfolded 25 packs together. The small tie provided at the edge of the sheet material enables the operator to sever a pack containing the required number of sheets from the web which issues from the machine. The cutting and 30 trimming of the packs in required lengths is effected in another machine which is without the scope of the invention and therefore need not further be referred to.

It is an object of the invention to arrange 35 the feed, guide and cutting rollers which act on the web material in its passage through the machine in overlapped relation whereby the initial threading between the operating parts is automatically effected and dispensing 40 with the necessity of employing auxiliary means, such as fingers, threading devices, vacuum and the like, to insure a uniform travel of the material through the machine.

45 A further object of the invention is to provide the guide rollers centrally of the bed rolls of the machine in resilient engagement therewith.

A further object of the invention constitutes 50 the provision of means for adjusting the resilient engagement between said guide rollers and bed rolls.

A further object of the invention includes the provision of means on the presser or 55 stripper fingers to engage the folded sheet upon removal from the bed rolls and to re-

lease the sheet incident to its delivery to a pack.

With these and other objects in view which will become apparent upon perusal of 60 the following specification, the invention then consists of the means hereinafter fully described and particularly pointed out in the claims.

The annexed drawings and the following 65 description set forth in detail the embodiment of the invention which, however, constitutes but one of the various ways in which the principle of the invention may be used.

In said drawings 70 Figure 1 is an end-elevation of a machine constructed in accordance with my invention.

Fig. 2 is a section on the line 2—2 of 75 Fig. 5.

Fig. 3 is a transverse sectional view of the machine.

Fig. 4 is a view of the machine from the opposite end to that shown in Fig. 1 and with the cutting and guiding rollers removed. 80

Fig. 5 is a detail view of one side of the machine, the upper rollers being removed to more clearly disclose the presser fingers on its shaft and the means for driving the 85 latter.

Fig. 6 is a top plan view of one side of the machine and

Fig. 7 is a diagrammatic view illustrating 90 the operation of the machine.

Referring to the drawings, 5 designates the main frame of an interfolding machine and serving as a support for the improved cutting and guiding means presently to be described. As is indicated in Fig. 1 a pair 95 of shafts 6 are journaled in bearings mounted on the machine frame 5 and extend transversely of the machine. The shafts are in parallel arrangement and spaced from one another to carry the body rolls 7 about which 100 the mutually overlapped sheets or webs are trained to be conducted downwardly to the folding mechanism. Laterally of the shafts 6 shafts 8 are arranged carrying a plurality of guide rollers 9 to direct the web material 105 onto the succeeding rollers which guide and cut the sheet material as hereinafter further explained. A pair of vertical brackets 10 are placed at the ends of the frame 5 and contain a plurality of bearings for sets of transverse shafts. A pair of transverse shafts 11, one for each bed roll 6 are equipped 110

with a plurality of rubber faced feed-rollers 12 in frictional engagement with the appertaining body rolls 7. Parallel to the shaft 11 a pair of shafts 13 for each body 5 roll are journaled in the bracket 10 and are likewise equipped with a plurality of sleeves 14 provided with transversely directed blades 15 coöperating with longitudinal recesses 16 in the bed rolls to cut the sheet material trained around the bed rolls. As clearly indicated in Fig. 6 the sleeves 14 of each set of shafts 13 are arranged in staggered relation whereby the blades 15 act successively to produce a single transverse cut 10 in the sheet material. Guide rollers 17 are arranged at equal distances from one another and are disposed so that their peripheral portions are in overlapping relation to the peripheral portions of the blades 15, whereby an equal and uniform guiding is obtained for the entire width of the sheet material passing through the cutting means, avoiding the tendency of the sheets to turn up immediately subsequent or 20 prior to the cutting operation and dispensing with the necessity of providing a vacuum or other auxiliary means to maintain the sheets in frictional engagement with the bed rolls 7.

30 The transverse cutting blades of each bed roll and the recesses of the latter are so arranged that the sheets pass between the bed rolls in mutually overlapped relation, whereby a continuous web of material issues from the bed rolls which is subjected 35 to the folding action by the means hereinafter further described. The knife carrying rollers or sleeves 14 are held against rotation on the shafts 13 by set screws 18 and thus 40 the sleeves may be readily adjusted to effect proper engagement between the blades 15 and the appertaining bed roll. The transverse cutting blades as will be recognized from Fig. 6 effect a continuous cut in trans- 45 verse direction of the web which cut, however, stops short of the longitudinal edges of the web whereby ties of a width of approximately one inch are obtained which leave the sheets continuous and interconnected but which connection may be easily 50 broken when after interfolding has been effected, a pack of the required number of sheets has been formed.

To guide the sheets after passing the transverse cutting blades 15 for proper movement between the body rolls a pair of shafts 19 are arranged at equal distances from the longitudinal axis of the machine and journaled in bearings 20 provided on 55 transverse rails 21 secured to the brackets 10. To the shafts 19 a plurality of arms 22 are secured which are bifurcated to receive between their prongs guide rollers 17 which are adapted to be held in resilient engagement with the bed rolls 7 and which,

as previously stated, have their peripheral portions in overlapping relation with respect to the blade 15. The hubs of the arms 22 are extended beyond the shafts 20 and the extensions 23 of the arms are interconnected by bolts 24 and tension springs 25. It is at once apparent that by adjusting the bolt 24 the tension under which the roller 17 is held in engagement with the appertaining bed roll 7 may be adjusted to 70 compensate for wear of the parts due to continuous operation. The machine is supplied with sheet material 27 by a pair of storage rolls (not shown) at one side of the machine and the material from the lower 80 roll is threaded immediately between the adjacent bed roll 7 and the feed rollers 12 and contacts with the guide rollers 9. The material 27 from the upper storage roll is trained about a pair of guide rolls 26 at 85 the upper end of the bracket 10, passes then downwardly encompassing the other guide rolls 9 and is threaded between the other bed roll 7 and the feed rollers 12 into the machine. Thus one side of the machine 90 is entirely open and access may be had thereto for the purpose of removing folded sheets from the machine. The sheet material 27 is fed downwardly to the folding mechanism and is guided in the passage by 95 means of suitable guides 28. A pair of stub shafts 29 are journaled in the main frame 5 below the body roll shafts 6 and are extended at one end beyond the frame to receive crank arms 32 of a pair of longitudinal shafts 33 journaled in the frame outwardly of the stub shafts 29. Due to this arrangement rotation of the shaft 33 will result in a rocking motion of the stub shafts 29. Carried on each stub shaft 29 100 105 is a folding drum comprising circular end plates 34 secured to the stub shaft and connected by an arcuate wall 35 at the periphery of the end plates and a radially extending wall 36 forming the extension of said wall 35. The free end of the arcuate wall 35 serves as an abutment to limit the movement of a finger 37, the outer end of which is formed to provide a binding ledge 38 while its inner end is pivoted as at 39 to the wall 36 and is placed under the influence of a spring 40 normally urging said finger against the free edge of the arcuate wall 35. The end plate 34, the arcuate wall 35 and the radial wall 36 are preferably formed integral as a single casting. 110 115

A plate 41 reciprocates in slots 42 in the end plates 34 and is slidably maintained on the outer face of the radial wall 36. The outer end of these plates 41 which clamp the overlapped sheets to the appertaining folding drum has a lug directed toward the arcuate wall 35 to form a clamping lip 43 adapted to coact with said wall. The lip is normally urged into clamping engagement 120 125 130

by a series of extensible springs 44 interposed between the wall 36 and lugs 45 at the inner end of the plate 41.

- 5 The ends of the clamping lips 43 are
adapted to coöperate with the bending ledge
38 of the opposite folding drum to clamp
the paper therebetween whereby a fold in
the paper is provided which fold is received
between the clamping lip 43 and its wall 35.
10 An arm 46 is pivoted to each stub shaft 29
and is secured in position by a screw 47
extending through a slot 48 in said arm and
entering into threading engagement with
the end plate 34. Each pair of arms carry
15 at the outer ends a transverse blade 49
adapted to force the fold between the wall
35 and the lip 43.

The movement of the clamping plates 41
is effected independently of the folding
20 drums by cam-disks 50 (Fig. 2) loosely
mounted on the stub shaft 29 at the ends of
the folding members and controlling rollers
51 carried on the ends of the clamping
plates 41. To the cam disks 50 links 52 are
25 pivotally secured which at the other ends
embrace cams 53 on the shafts 33.

The bending ledge 38 comes into contact
with the opposite clamping lip before the
same reaches its upper limit and thereby
30 stretches the paper before the opposite
clamping lip releases the paper. The bending
ledge, therefore, does not only bend the
paper prior to being acted on by the tuck-
ing blade but it also prevents the upper end
85 of the sheet from dropping or sagging.

The folding members are continuously
rocked, approximately through one quarter
of a revolution and the upper limit of oscillation
40 if the bending ledges 38 and clamping
45 lips 43 lies substantially in the horizontal
plane passing through the axis of oscillation
of the folding member. The lower limit
of oscillation of the clamping lip is at the
vertical plane passing through the axis of
oscillation of the folding members, so that
50 the folds held by the clamping lips are dis-
posed horizontally when released.

As the inner side of a clamping member
55 rocks upwardly, its clamping lips 53 will
move into the recess of the bending ledge
38 to bend the paper and prepare the same
for the action of the tucking blade 49 above
the ledge 38. The tucking blade 49 moves
then downwardly between its appertaining
55 ledges 38 and the wall 35 of the drum and
forces the fold of paper between the lip 43
and the wall 35. The tucking blade is then
moved upwardly and the clamping plate 41
moves inwardly whereby its lip 43 clamps
60 the fold against the wall 35. When the fold
carrying member reaches its lower limit of
oscillation the fold of the sheet is released
by engagement of the rollers 51 of the plate
41 with portions 54 of the cams 50. This
65 release occurs when the clamping lip 43 of

the plate 41 is above the side edge of an end-
less conveyer belt adapted to receive the in-
terfolded sheets. The entire operation de-
scribed is repeated alternately with respect
to the folding members. To properly ar-
range the sheet material on the delivering
means a series of presser or stripper fingers
55 are disposed at each side of the folding
drums on shafts 56 each of which is rocked
by means of an arm 57, carried by said shaft
70 and carrying a roller in engagement with
a cam 58 on the corresponding shaft 33. A
spring 59 connects the lower ends of arms
60 secured to the shafts 56 whereby the
fingers 55 are held by the cam in engage-
75 ment with the folded sheet material. The
fingers are all raised only momentarily by
the cam incidentally to the releasing move-
ment of the clamping plates. In the raised
position the fingers enter grooves 84 formed
80 in the wall of the folding members to en-
gage the upper faces of the sheet material.
The presser fingers 55 are provided with
flat springs 61 pivotally mounted to said
fingers intermediate their ends and main-
tained in position by arms 62, secured to a
transverse shaft 63 which extends through
85 all of the presser fingers of one set (Fig. 5).
At the outer end of this shaft 63 an arm 64
is provided bifurcated at its outer end to
90 carry a roller 65 in engagement with the
cam 66 loosely maintained on the shaft 56.
Integral with the cam 66 or secured thereto
is a gear 67 meshing with a gear 68 keyed
to the shaft 33; set collars 69 are placed on
100 each side of the gear 67 and a cam 66 to
prevent displacement thereof. The rotation
of the cam 66 as is obvious is independent
of the revolution of the shaft 56 on which it
is loosely mounted. The action of the gears
105 and cam is so timed as to bring the spring
61 against the under side of the presser
fingers 55 when the same are in the upward
position to receive a folded sheet. When
the clamping lip 43 carries a folded sheet
110 around toward the bottom, the edges of the
sheet will be received between the spring 61
and the finger 55 and is subsequently re-
leased by drawing the spring 61 backwardly
over an incline as indicated in Fig. 7.

115 The drive to the various parts of the ma-
chine is obtained from one of the shafts 33
which is rotated by any suitable source of
power. Gears 70 of the shafts 33 mesh with
other gears 71 which actuate gears 72 keyed
120 to the shafts 6. The gear wheel 72 of each
bed roll shaft 6 meshes with a gear 82 on
the adjacent ends of the shafts 11 and 13.
The gears 82 by reason of their proximity
are laterally spaced, the gear 72 having a
125 width sufficient to mesh with both of said
gears 82.

130 The conveyer belts 73 are trained around
sprocket wheels 74 mounted on a shaft 75,
journaled in the main frame 5. One end of

the shaft carries a ratchet wheel 76 which is engaged by a pawl 77 of a lever 78 loosely mounted on the shaft 75. The outer end of the lever 78 is interconnected by a pitman 5 79 to a crank pin 80 on the outer end of one of the shafts 29.

Upon rotation of the shaft 29 an intermittent movement is imparted to the shaft 75. The remote end of the conveyer chains 10 encompasses sprocket wheels 81 mounted on a shaft 83 also secured to the main frame.

The drawings illustrate the preferred embodiment of my invention by way of example. It is understood that a large number of alterations and modifications will suggest themselves to those versed in the art and I, therefore, do not intend to limit myself to the structure precisely as shown, but want to avail myself of any changes constituting departures within the scope of my invention as defined in the appended claims.

I claim:

1. In a machine of the character described, in combination with a bed roll, a plurality 25 of feed rollers engaging said bed roll at one side thereof, a rotatable transverse cutting means acting on a web of work material fed over the carrier encompassing said bed roll, and guide rollers engaging said bed 30 roll opposite that side in engagement with the feed rollers, said transverse cutting means and said feed and guide rollers having peripheral portions in overlapped relation to guide work material between them and 35 said bed roll.

2. In a machine of the character described, in combination with a bed roll, a plurality of feed rollers in transverse alignment engaging said bed roll at one side 40 thereof, a plurality of rollers having knife blades to cut the material on the bed roll in transverse direction and guide rollers engaging said bed roll at the other side thereof, said feed and guide rollers and blade 45 equipped rollers having peripheral portions in overlapped relation to guide work material between them and said bed roll.

3. In a machine of the character described, in combination with a bed roll, a 50 shaft carrying a plurality of spaced feed

rollers in engagement with said bed roll, a pair of shafts parallel to said bed roll and equipped with blade carrying rollers to cut the material on the bed roll in transverse direction, and a plurality of guide rollers engaging said bed roll opposite that side engaged by said feed rollers all of said feed, guide, and cutting rollers having peripheral portions in overlapped relation to guide work material between them and said bed 55 roll.

4. In a machine of the character described, in combination, a pair of bed rolls, transverse cutting means acting on material encompassing said bed rolls, sets of guide 60 rollers interposed between said bed rolls, and adjustable means for maintaining said sets of guide rollers in yielding engagement with appertaining bed rolls.

5. In a machine of the character described, in combination, a pair of bed rolls, transverse cutting means acting on material encompassing said bed rolls, a pair of shafts disposed above said bed rolls, guide 65 rollers loosely secured to said shafts, and adjustable means for maintaining yielding engagement between said guide rollers and appertaining bed rolls.

6. In a machine of the character described, in combination, a pair of bed rolls, transverse cutting means acting on material encompassing said bed rolls, a pair of shafts above said bed rolls, guide rollers secured to said shafts, and adjustable spring connections for said guide rollers to maintain 80 the same in resilient engagement with appertaining bed rolls.

7. In a machine of the character described, in combination, a pair of bed rolls, transverse cutting means acting on material 90 encompassing said bed rolls, a pair of shafts above said bed rolls, arms loosely mounted on said shafts, rollers carried by said arms and adjustable spring connections for said arms to maintain said guide rollers in engagement with the appertaining bed rolls.

In testimony whereof I hereunto affix my signature.

LOUIS ALBERT STRAUBEL.
